UNITED STATES PATENT OFFICE

WILHELMUS PETRUS VAN LAMMEREN, OF VOORSCHOTEN, NETHERLANDS, ASSIGNEE
TO U. S. SLICING MACHINE COMPANY, OF LA PORTE, INDIANA, A CORPORATION
OF INDIANA

SLICING MACHINE

Application filed May 5, 1928, Serial No. 275,401, and in Great Britain May 25, 1927.

In machines for slicing meat and other substances, the substance to be sliced by the knife of the machine is generally clamped to a feed plate by means of a clamp or press including a clamp bar or equivalent (hereinafter referred to simply as a clamp bar) supported on one or two upstanding uprights from the feed plate. In some constructions, the clamp bar is normally locked to the uprights, but can be released at will from it, or from either or both of them, in order to move the bar into any desired position relatively to the feed plate. Various devices, such as cams, detents, and friction rings, are in present use for locking clamp bars to their uprights, and the object of this invention is to provide an improved device for this purpose.

In accordance with this invention, the improved device for locking the clamp bar to its upright, or each of its uprights, is characterized by a spring which is coiled around and normally clutches the upright, but which can be released therefrom at will. The spring may be so arranged that its clutching action can be relieved by pressing on one of its ends and may also be arranged that, when a pressure is applied to the clamp bar in either direction parallel to the upright, the clutching action of the spring will automatically increase.

In a preferred construction, in which a clamp bar is pivotally carried by sleeves slidably mounted on two uprights, springs are coiled around the uprights and are operatively connected, at their ends, to the sleeves, the arrangement being such that the springs normally clutch the uprights, and thereby lock the sleeves thereto, but can be released at will, so that the sleeves, and the clamp bar therewith, can be shifted. If desired, means may be provided whereby the springs can be released either individually or simultaneously, said means being preferably arranged on a handle extending from the clamp bar, so that the latter can be manipulated by one hand.

The invention is illustrated by way of example in the accompanying drawing in which—

Fig. 1 is an elevation of a clamp having the improved locking device applied thereto;

Fig. 2 is a fragmentary view showing part of Fig. 1 in vertical section; and

Figs. 3, 4 and 5, respectively, are sections on the lines III—III, IV—IV and V—V of Fig. 1.

Referring to the drawing, the fixed upright 1 and hinged upright 2 represent known parts of the usual press of a slicing machine, the usual feed plate being indicated conventionally by the line A.

The sleeves 3 and 4 are slidably mounted on the uprights 1 and 2, respectively. Each of the sleeves 3 and 4 is pivotally connected by screws 5 or 6 to a clamp bar 7 near one or other end thereof. For manipulation of the bar 7, the latter is provided with a handle 8. The clamp bar 7 is formed with an eye 9 and with a forked end 10 for the passage of the sleeves 3 and 4, the eye and the fork being so dimensioned as to permit the clamp bar to be inclined relatively to the feed-plate.

Each sleeve 3 or 4 is so formed as to provide an annular recess 11 between it and the relative upright, each recess 11 being adapted to house a helical spring 12 or 13 coiled round the upright. The upper and lower ends 12^a, 12^b and 13^a, 13^b of the springs 12 and 13 are bent outwards and respectively pass through triangular apertures 14^a, 14^b and 15^a, 15^b, in the sleeves 3 and 4. In the construction shown, the lower end 12^b of the spring 12 is connected to a knob 16 while the upper end 13^a of the spring 13 is connected to a knob 17. The apertures 14^a, 15^a, through which pass the ends of the spring connected to the knobs 16, 17, are formed with slots 14^c, 15^c. The upper ends of the recesses 11 are closed by caps 18 screw-threaded into the sleeves.

The springs 12 and 13 are wound to opposite hands, the former being left-handed while the latter is right-handed. Further, the normal internal diameter of the springs 95 is slightly less than the diameter of the uprights, so that, normally, the springs tightly clutch the uprights and thereby lock with a frictional grip the sleeves and the bar in position thereon. By displacing the knob 16 or 100

17 into the slot 14^c or 15^c, the relative sleeve 3 or 4 is thereby enabled to be shifted along the upright as desired. The knob 16 may be engaged and displaced directly by the operator's finger whereas the knob 17, as shown, is adapted to be displaced by his thumb through the intermediary of a rod 19, having at one end a knob 19^a. The rod 19 extends along the bar 7, through guides 20, from the sleeve 4 to the handle 8. With this arrangement, by pulling on the knob 16 with finger and pressing on the knob 19^a with his thumb, the operator can release both or either of the springs 12, 13, so that the bar 7 can be manipulated entirely by one hand. When the operator withdraws his finger and thumb from the knobs 16 and 19^a, the springs will return automatically to the position in which they clutch the uprights.

23 The triangular apertures are each formed with an inclined face 14^d or 15^d, against which the adjacent bent end of the relative spring 12 or 13 bears. Should upward pressure (for example, the reaction of the substance being clamped) be brought to bear on the sleeves, the springs will be caused to grip the uprights more tightly by the action of the inclined faces 14^d and 15^d of the upper apertures 14^a and 15^a. The springs would be similarly tightened, should downward pressure (for example, the weight of the bar) be brought to bear on the sleeves by the action of the faces 14^d and 15^d of the lower apertures 14^b and 15^b.

33 The apertures 14^b and 15^a are closed by flanges 16^a and 17^a on the knobs 16 and 17. The form of press illustrated has been chosen simply for the purpose of illustration and it will be obvious that the invention could be readily applied to other kinds of clamping presses without departing from the scope of this invention. The clamp bar might have two handles, or the sleeves carrying it might each have one, each handle being associated, if desired, with means for relieving the clutching action of the relative spring. Obviously, the sleeve members could constitute the stationary supports with the upright or rod members slidably mounted therein and carrying the clamp bar.

I claim:

1. In a work clamp for slicing machines, a sleeve member, a rod member disposed in said sleeve member, one of said members being guided for sliding movement by the other of said members and a clamp bar carried by said sliding member, a friction element disposed between said members frictionally engaging said rod member to releasably hold said members against relative sliding movement, said friction element having a separate releasing means connected therewith and supported on one of said members to disengage said friction element from said rod

member and permit relative movement between said members.

2. In a work clamp for slicing machines, a sleeve member, a rod member disposed in said sleeve member, one of said members being guided for sliding movement by the other of said members, a clamp bar carried by said sliding member, a spring disposed between said members tending normally to grip said rod member and hold said members against relative movement.

3. In a work clamp for slicing machines, a sleeve member, a rod member disposed in said sleeve member, one of said members being guided for sliding movement by the other of said members, a clamp bar carried by said sliding member, a spring disposed between said members tending normally to grip said rod member and hold said members against relative movement, said spring having a releasing means connected therewith to disengage said spring from said rod member and permit relative movement between said members.

4. In a work clamp for slicing machines, a sleeve member, a rod member disposed in said sleeve member, one of said members being guided for sliding movement by the other of said members, a clamp bar carried by said sliding member, a helical spring disposed around said rod in said sleeve, said spring tending normally to grip said rod member and hold said rod member and sleeve member against relative movement.

5. In a work clamp for slicing machines, a sleeve member, a rod member disposed in said sleeve member, one of said members being guided for sliding movement by the other of said members, a clamp bar carried by said sliding member, a helical spring disposed around said rod in said sleeve, said spring tending normally to grip said rod member and hold said rod member and sleeve member against relative movement, said spring having a releasing member connected therewith and positioned outside of said sleeve, said releasing member being operable to lessen the grip of said spring on said rod and permit relative movement between said rod and sleeve.

6. In a work clamp for slicing machines, a sleeve member, a rod member disposed in said sleeve member, one of said members being guided for sliding movement by the other of said members, a clamp bar carried by said sliding member, a helical spring disposed around said rod in said sleeve, said spring tending normally to grip said rod and hold said rod member and sleeve member against relative movement, the ends of said spring being held by said sleeve, one of said ends being extended through a slot in said sleeve.

7. In a work clamp for slicing machines, a rod member, a sleeve member slidably mounted thereon, a clamp bar carried by said

5 sleeve member, a helical spring disposed around said rod member in said sleeve tending to grip said rod member and hold said members against relative movement, said sleeve member having inclined faces upon which the ends of said springs bear, said inclined faces tending to wrap said spring more tightly around said rod member when force is applied tending to move said sleeve member on said rod member.

10 8. In a work clamp for slicing machines, a rod member, a sleeve member slidably mounted thereon, a clamp bar carried by said sleeve member, a helical spring disposed around said rod member in said sleeve tending to grip said rod member and hold said members against relative movement, said sleeve member having orifices therein with inclined faces upon which the ends of said 15 spring bear, one of said ends extending through said sleeve to provide manually operated means for disengaging said spring from said rod member.

20 9. In a work clamp for slicing machines, a pair of rod members having sleeves slidably mounted thereon, a clamp bar having a handle portion carried by said sleeves, a retaining element associated with each sleeve and rod member to engage said rods and hold said sleeves thereon, means positioned on one of said sleeves and adjacent said handle portion operative to disengage both of said retaining elements from said rod members to permit said sleeves to slide on said 25 30 35 rod members, said retaining elements being yieldingly urged to re-engage said bars upon the release of said means.

40 10. In a work clamp for slicing machines, a pair of rod members having sleeves slidably mounted thereon, a clamp bar having a handle portion carried by said sleeves, a retaining element associated with each sleeve and rod member to engage said rods and hold said sleeves thereon, finger operated releasing means connected to one of said retaining elements, and thumb operated releasing means connected to the other of said retaining elements, both of said releasing means being positioned adjacent said handle portion to be easily accessible to the hand of the operator manipulating said clamp bar.

45 55 60 65 11. In a work clamp for slicing machines, a pair of rod members having sleeves slidably mounted thereon, a clamp bar having a handle portion carried by said sleeves, a retaining element associated with each sleeve and rod member to engage said rods and hold said sleeves thereon, finger operated releasing means movable toward said handle and connected to one of said retaining elements, and thumb operated releasing means connected to the other of said retaining elements, said thumb operated releasing means being mounted for movement in a direction substantially opposite to the direction of move-

ment of said finger operated releasing means.

12. The combination set forth in claim 10 wherein said retaining elements are automatically urged to re-engage said bars after their disengagement therefrom by said releasing means.

13. The combination set forth in claim 11 wherein said retaining elements are automatically urged to re-engage said bars after their disengagement therefrom by said releasing means.

14. In a work clamp for slicing machines, a pair of supports, a sleeve slidably mounted on each of said supports, a clamp bar having a handle portion carried by said sleeves, coil springs wound around said supports and disposed between said supports and sleeves tending to normally grip said supports, one of said springs being wound around said support in a direction opposite to the other spring, releasing means connected to said springs, said releasing means being positioned accessible from said handle portion.

15. In a work clamp for slicing machines, a pair of supports, a sleeve slidably mounted on each of said supports, a clamp bar having a handle portion carried by said sleeves, coil springs wound around said supports in opposite directions, said springs being disposed between said sleeves and supports and tending normally to grip said supports, the ends of said springs extending through orifices in said sleeves, one of said sleeves having finger engaging means and the other a thumb engaging means, both of said means being positioned accessible from said handle portion.

16. A work clamp for slicing machines comprising a pair of uprights adapted to be mounted on a slicing machine table, a sleeve slidably mounted on each of said uprights, a spring surrounding one of said uprights and connected to the sleeve on said upright for resisting movement of said sleeve along said upright, and a clamping bar supported by said sleeve.

17. A work clamp for slicing machines comprising a pair of uprights adapted to be mounted on a slicing machine table, a sleeve slidably mounted on each of said uprights, a spring surrounding one of said uprights and connected to the sleeve on said upright for resisting movement of said sleeve along said upright, a clamping bar supported by said sleeve, and means for rendering said spring inoperative to permit movement of the sleeve to which said spring is connected along the upright upon which said sleeve is mounted.

18. A clamp for slicing machines comprising an upright, a member adapted to slide along said upright for supporting a clamping bar, a spring connected to said member and adapted to engage said upright to prevent movement of said member along said upright, and an inclined surface on said member adapted to be engaged by one end of said

spring and to hold said spring in gripping engagement with said upright while permitting the end of the spring to be moved against the action of said inclined surface to release the spring from gripping engagement with said upright and permit movement of said member along said upright.

19. A clamp for slicing machines comprising a clamping bar, a pair of sleeves for supporting said clamping bar, each of said sleeves being slidable along separate uprights on a slicing machine work supporting table, springs within said sleeves adapted to encircle their respective uprights and normally urged into gripping engagement with said uprights, and inclined surfaces on each of said sleeves adapted to increase the gripping action of said springs on said uprights when force is applied to said sleeves to move them along said uprights in either direction.

20. A device as claimed in claim 19 in which one of said uprights is adapted to be pivoted to said slicing machine table.

21. A device as claimed in claim 18 in which means are provided for releasing said springs.

22. A clamp for slicing machines comprising a clamping bar, a sleeve for carrying said clamping bar, an upright upon which said sleeve is slidably mounted, said upright adapted to be supported upon the table of a slicing machine, a coiled spring housed within said sleeve and surrounding said upright, the internal cross-sectional area of said spring being normally less than the cross-sectional area of said upright so that when the spring is expanded over said upright it tends to grip said upright and prevent movement of said sleeve longitudinally of said upright, and means arranged in a position to operatively engage said spring and increase its internal cross-sectional area sufficiently to permit relative longitudinal movement between said sleeve and said upright.

23. A clamp for slicing machines comprising a clamping bar, a sleeve for carrying said clamping bar, an upright upon which said sleeve is slidably mounted, said upright adapted to be supported upon the table of a slicing machine, and a coiled spring housed within said sleeve and surrounding said upright, the internal cross-sectional area of said spring being normally less than the cross-sectional area of said upright so that when the spring is expanded over said upright it tends to grip said upright and prevent movement of said sleeve longitudinally of said upright.

In testimony whereof I have signed my name to this specification on this 17th day of April, A. D. 1928.

WILHELMUS PETRUS van LAMMEREN.
